F. M. LAY

WAGON STAKE

Filed March 19, 1920

FIG. 2.

FIG. 3.

FIG. 1.

Witness:
E. Williamson

Inventor:
Francis M. Lay

By W. G. Johnston
Attorney

UNITED STATES PATENT OFFICE.

FRANCIS M. LAY, OF MOLINE, ILLINOIS, ASSIGNOR TO DEERE & COMPANY, OF MOLINE, ILLINOIS, A CORPORATION OF ILLINOIS.

WAGON STAKE.

Application filed March 19, 1920. Serial No. 367,153.

To all whom it may concern:

Be it known that I, FRANCIS M. LAY, a citizen of the United States, residing at Moline, in the county of Rock Island and State 5 of Illinois, have invented certain new and useful Improvements in Wagon Stakes, of which the following is a specification, reference being had therein to the accompanying drawing.

10 My invention relates to wagon stakes, and more particularly to a type which can be readily replaced when necessary, or as readily removed for shipping, storage or other purposes, as fully set forth in the following specification and claim.

Ordinarily wagons are shipped knocked down and are assembled when they reach their destination, and, as ordinarily shipped, the bolsters and stakes are secured together 20 as when the wagon is in use, consequently a bolster, with a stake at each end, presents a form awkward to ship or put in storage, and also awkward to handle except in assembling the wagon, and the result is that many 25 stakes are broken or sufficiently damaged to require replacement by others in perfect condition.

And the object of my invention is to produce a stake as a new article of manufacture that can be carried in quantity by dealers as an extra part, that can be shipped 30 or stored independently of other parts of a wagon, and that can be mounted on any bolster after making therein suitable holes 35 for the bolts.

Referring to the drawings in which similar numerals indicate identical parts—

Figure 1 is a side elevation of my improved stake attached to a wagon bolster.

Figure 2 is an enlarged front view similar to Figure 1, but omitting the bolster, and

Figure 3 is a side elevation of Figure 2.

The stake body 1 is made preferably of wood and has its lower end rigidly secured 40 in a socket in a casting 2 by rivets 3. The base of the casting 2 is extended to form a foot 5 and flanges 4 to present a broad surface to rest on a bolster 6 to ensure stability when the stake is secured in place. A metallic band 7 is secured to the inner side of the stake body and is bent over the top 45 thereof to extend down the opposite side and is then extended outwardly and down-

wardly to form a brace 8, the end 9 being turned in horizontally and secured to the 55 foot 5 by a bolt 10 which with strap bolts 11 and 12, rigidly attach the casting to the bolster 6.

The strap-bolts 11 and 12 are secured to the stake 1 by one of the rivets 3, which 60 passes through the sides of the casting 2 and the stake proper and the strap ends 13 of the bolts 11 and 12, and by a similar rivet 14 at the upper end of the straps. Stake rings 15 and 16 are pivotally secured between the 65 band 7 and the stake body 1 for the purpose of holding an extra and higher stake as shown in dotted lines in Figure 2.

I have shown and described a structure 70 in which the parts are assembled to withstand the strains and rough usage to which a device of this type is ordinarily subjected. The strap portions of the bolts 11 and 12 extend to embrace a substantial part of the 75 length of the stake to provide a maximum of resistance to a side thrust and to add to the efficiency of the brace 8; the bolts 11 and 12, with which the straps 13 are integral respectively, project through the bolster and are firmly secured thereto, the 80 bolt 10 also extending through the bolster and rigidly securing the foot 5 of the casting and the end 9 of the brace 8 to the bolster.

What I claim is—

A stake adapted to be mounted on a wagon bolster and including a casting on the bolster having a base extending from opposite sides thereof and an outwardly extending foot, a socket in said casting, a wood 90 stake body rigidly secured in said socket, a metallic band secured to the inner side of the stake body and bent over the top thereof and secured on the outward side of the stake body for part of the length thereof 95 and extending downwardly and outwardly therefrom, having its end portion bent inwardly to rest on said foot, a bolt securing said portion and foot to the bolster, and bolts having strap portions projecting upwardly and riveted to the front and rear sides of the stake body and the casting, said bolts passing through the bolster and secured thereto.

FRANCIS M. LAY.
